CHICKEN COUNTING MACHINE

Harvey B. Harnar, Lawrence, Kans.

Application December 8, 1938, Serial No. 244,709

7 Claims. (Cl. 119—1)

This invention relates to an improved counting machine particularly adapted for counting chickens, but likewise adaptable for counting other fowl or for counting animals.

More particularly, it is an aim of this invention to provide a portable machine adapted to be positioned at the exit of a chicken house or between chicken pens and through which the chickens must pass in leaving the house or in passing from one pen to the other, and which will be actuated by the chickens passing therethrough for counting the chickens leaving the pen or house.

More particularly, it is an aim of this invention to provide a counting device having a depressible platform over which the chickens must pass, said platform being depressed by the weight of the chickens for actuating the counting mechanism and for simultaneously actuating a plurality of closures by means of which only one chicken or fowl may be admitted or released from the machine.

Still a further aim of the invention, is to provide a pair of normally open gates disposed adjacent the entrance end of the machine and contiguous with the hinged end of a depressible platform to be closed by a chicken stepping on the platform to prevent more than one chicken from being on the platform at any time and to prevent the chicken once on the platform from backing off of it so as to be counted more than once; and a pair of doors, at the exit end of the passageway likewise connected to the platform to be opened when it is depressed for permitting the chicken to pass out of the machine.

Still a further object of the invention is to provide a pair of normally closed doors at the entrance end of the machine for normally closing the machine, when not in use, and means for holding said doors in a partially open position so that chickens may enter the machine but will be prevented from leaving through the entrance end thereof.

Other objects and advantages of the invention will hereinafter become more fully apparent from the following description of the drawings, which illustrate a preferred embodiment thereof, and wherein:

Figure 1 is a longitudinal vertical sectional view of the machine,

Figure 2 is a horizontal sectional view taken along the line 2—2 of Figure 1,

Figure 3 is a vertical transverse sectional view taken along the line 3—3 of Figure 1, and

Figure 4 is an enlarged vertical sectional view,

partly in elevation, illustrating the counting mechanism.

Referring more particularly to the drawings, wherein like reference characters designate like or corresponding parts throughout the different views, 10 designates generally the casing or box which comprises the base or bottom 11, sides 12 and top 13. The box 10 is open at its opposite ends, the end designated by the arrow 14 constituting the entrance, and the end designated by the arrow 15 constituting the exit of the box.

At the entrance end 14 of the box 10 a series of steps 16, is provided, which extend inwardly and upwardly from the bottom 11. A platform 17 is hinged or pivoted at 18 to the inner or uppermost step 16, and extends therefrom to a point adjacent the exit end 15. Platform 17 is provided with the oppositely disposed upwardly extending flanges 17', which lie flush against the sides 12, for a purpose which will hereinafter be described.

An expansion coil spring 19 is disposed between the bottom 11 and platform 17 to normally hold it in a raised position substantially parallel to the bottom 11, as in Figure 1.

A pair of brackets 20 secured to the sides 12 adjacent the entrance end 14 journal the vertically disposed rods 21 to which are secured the doors 22 by the brackets 23. Springs 24 normally hold doors 22 in a closed position to close the entrance end 14 of the casing 10 when the machine is not in use. A latch or stop 25 is pivotally mounted intermediate of its ends at 26 to the under side of the top 13 and has the downturned ends 27 to engage the doors 22, when the member 25 is disposed transversely of the box 10, to hold the doors in their partly open position, as best seen in Figures 2 and 3.

A pair of gates 28 are hinged to the sides 12 by the brackets 29 and are normally disposed in an open position, against the sides 12 and extending toward the exit end 15. Gates 28 are preferably hinged at a point substantially in a vertical line with the hinged end 18 of the platform 17. A pair of doors or gates 30 are hinged to the sides 12 by corresponding brackets 29, at the exit end 15 of the box 10 and are normally disposed in a closed position, as best seen in Figures 1 and 2. Gates or doors 30 are preferably formed of a large heavy gage mesh wire fabric as are likewise the gates 28, while the doors 22 are solid, being preferably formed of sheet metal.

T-shaped levers, designated generally 31, are pivotally mounted on the sides 12 at the junction of their three arms, as indicated at 32. The levers 31 have the corresponding arms 33 and 34

with eyelets 35 at their free ends. The corresponding depending arms 34 of the levers 31 are connected by their eyelets 35 to the links 36 which are connected at their opposite ends to the 5 cranks 37 secured to the gates 28, while the links 38 similarly connect the corresponding arms 33 to cranks 29 which are secured to the doors 30. The third arm 40, of each of the levers 31, which is disposed substantially at right angles to the arms 10 33 and 34 to form with each of said arms a bell crank, is provided with the flat free end 41 provided with a plurality of openings adapted to selectively receive an end of a link 42 the opposite end of which extends through and is bent to 15 form a hook to engage the platform 17. It will thus be seen that each of the levers 31 is connected by a link 42 to the platform 17 and also connected by a link 36 and 38 to a gate 28 and a door 30, respectively.

20 As best seen in Figure 1, a cover 43 is hinged at 44 to the top 13 and may be secured in a closed position by a swinging latch 45 to form the compartment 46 in which is disposed the counting mechanism, designated generally 47. The counting mechanism 47 comprises the inverted U-shaped support 48 which is secured to the top 13 and disposed in the compartment 46 and between the upwardly extending free ends of which is secured an axle 49. Journalled on the axle 49 25 are the three wheels 50, 51 and 52, the periphery of each of which is calibrated in numerals from 0 to 9, as best seen in Figure 3. A flange 53 projects from the corresponding side of each of these wheels and forms a segment of a circle having its opposite ends spaced to form the openings 54. Each of the flanges 53 is provided with nine 30 equally spaced notches 55 to correspond with the calibrations on the peripheries of the wheels. A U-shaped member 56 has its terminal ends loosely 35 mounted on the axle 49 on the outer side of the wheels and between the uprights of the member 48 and at one side is provided with an arm 57 forming a continuation of one of the legs of the member 56, and which is provided with a plurality of spaced openings, as best seen in Figure 4. A rod 58 extends between the legs of the U-shaped member 56 and is disposed adjacent to the intermediate portion thereof, to pivotally mount a U-shaped member 59 the legs of which 40 are loosely mounted on the rod 58. The intermediate portion or bar 60 of the member 59 depends downwardly from the rod 58 and is provided with a plurality of depending dogs 61, 62 an 63 of decreasing length. Each of these dogs 45 has an inturned tapered end 64 and as best seen in Figure 3, the dog 61 extends inwardly to engage the notches of the flange 53 of wheel 50, while dog 62 is adapted to engage the notches of the flange of wheel 51, and dog 63 the notches 50 of the flange of wheel 52. Inasmuch as dog 61 is longer than dog 62 and dog 62 is longer than dog 63, when the dog 61 has its end 64 engaging one of the notches 55 of its flange 53, dogs 62 and 63 will be thereby held out of engagement 55 with the notches 55 of the other two flanges 53. A coil spring 65, carried by rod 58 and having one of its terminals engaging bar 60 and the other terminal engaging the intermediate portion of the U-shaped member 56, urges the dogs toward the flanges 53. A link 66 has one of its ends selectively positioned in one of the openings of the arm 57 and its opposite end selectively positioned in one of the openings of an arm 40 of one of the levers 31 to connect the counting mechanism 70 75 47 to the platform 17.

From the foregoing it will be seen, that each time that the arm 57 is drawn downwardly by the link 66 that the dog 61, which is in engagement with one of the notches 55 will turn the wheel 50, in a counterclockwise direction as seen in Figure 4, the length of one of its notches and the distance of one numeral on the periphery of the wheel 50 so that a complete revolution of the wheel 50 would ordinarily constitute a count of 10. As the dog 61 reaches the zero mark on the wheel 50, constituting the end or the revolution of the wheel, end 64 of the dog will be urged into the space 54 by the spring 65 allowing the dog 62 to engage the first notch 55 of the flange 53 of wheel 51 to turn it until the numeral one is exposed in line with the zero on wheel 50. It will thus be seen that after each ten movements of the wheel 50 the wheel 51 will be moved one-tenth of a revolution and after ten movements of wheel 51, wheel 52 will be moved, a tenth of a revolution, because at this point the opening 54 of the flanges 53 of both the wheels 50 and 51 will be aligned and positioned to receive the ends 64 of the dogs 61 and 62 allowing dog 63 to be projected into engagement with its flange 53. The counting mechanism 47 as illustrated is thus adapted for counting up to nine hundred and ninety-nine and obviously additional wheels may be provided if the counting mechanism 47 need be adapted for even greater numbers. 10 15 20 25 30 35 40 45 50 55 60 65 70 75 80 85 90 95 100

As best seen in Figure 4, leaf springs 67 are secured to the support 48 and positioned so that their free ends engage the notches 55 of the three flanges 53 to prevent the wheels 50, 51 and 52 from being accidentally revolved. 30

From the foregoing description, it will be obvious that the doors 22 may be manually opened and positioned in an open position by the latch member 25 and in this position they will project inwardly of the casing 10 and be disposed obliquely thereto so that a fowl or animal may enter through entrance 14 past the doors 22, which can give inwardly if necessary, to allow the fowl or animal to pass but which will prevent the fowl or animal from leaving through entrance 14 due to the inwardly converging relationship of the two doors 22. Assuming that the machine 10 is being used to count chickens, the chicken passes in through entrance 14 as heretofore described, up the steps 16 and onto the platform 17. At the time that the chicken steps onto the platform 17 gates 28 are in an open position, as illustrated in Figure 1, and doors 30 are in a closed position, as seen in Figure 2. As the chicken moves toward the gate 30 its weight will depress platform 17 against the action of the coil spring 19 thereby drawing links 42 downwardly to rock levers 31 in a clockwise direction, as seen in Figure 1, to simultaneously swing gates 28 to a closed position and gates 30 to an open position. It will thus be seen, that only one chicken can step on the platform 17 at any time as the gates 28 will prevent a second chicken from moving onto the platform and these gates will likewise function to prevent a chicken on the platform from backing off so as to be counted twice. As soon as the chicken on the platform 17 leaves through the exit 15 the platform will be raised by spring 19 to close doors 30 and open gates 28 by the operation of links 42 which swing levers 31 in an opposite or counterclockwise direction. Since one of the levers 31 is connected to arm 57 by the link 66 the platform 17 will likewise actuate the counting mechanism 47 each time that the platform is depressed so that an accurate count of the chick- 75

ens passing through casing 10 will be obtained. Should a chicken fly through the casing 10 without touching platform 17 and force the doors 30 open as it passes out of the casing, the door 30 will actuate the levers 31, one of which is connected to the counting mechanism 47, which will be actuated thereby in the same manner as when platform 17 is depressed. The upwardly projecting flanges 17' will prevent any trash, carried on to the platform by the chickens, from dropping down between the sides 12 and platform 17 to prevent the platform from being fully depressed; and will also prevent the chickens' toes from becoming wedged between the sides of the platform 17 and the sides 12.

Various modifications and changes in the construction and arrangement of the parts forming the invention are contemplated and may be resorted to, as the drawings and description are only intended to illustrate a preferred embodiment thereof, and the right is therefore expressly reserved to make such variations and changes as fall within the spirit and scope of the invention as hereinafter defined by the appended claims.

I claim as my invention:

1. In a device of the class described, a box having open ends forming an entrance and exit, respectively, steps disposed adjacent the entrance end of the box, a platform hinged to the topmost of said steps and extending therefrom toward the exit end of the box, spring means normally retaining said platform in a raised position, normally closed hinged door means mounted at the exit end of the box, normally open hinged gate means mounted adjacent the hinged end of the platform, lever means pivotally connected to the box, links connecting the door means, gate means and platform to the lever means for closing the gate means and opening the door means when the platform is depressed whereby one chicken at a time may pass through the box, doors hinged to the sides of said box at the entrance end thereof, spring means normally holding said doors in a closed position, and latch means for retaining said doors in a partly open position whereby the chickens may enter said box but may not leave it through the entrance end thereof.

2. A fowl passageway comprising an elongated casing provided with open ends forming an entrance and an exit, a raised platform hinged adjacent the entrance end of said casing and extending to the exit end thereof, spring means normally holding said platform in a raised position, gates hinged to the sides of said casing, adjacent the entrance end thereof, and normally disposed in an open position, doors hinged to the sides of said casing, at the exit end thereof, and normally disposed in a closed position, T-shaped levers hinged at their intersection points to the sides of said casing, links connecting the corresponding ends of said levers to said gates and doors, and links connecting the other ends of said levers to said platform whereby the doors will be opened and the gates closed by depressing the platform so that only one chicken at a time may pass through the machine.

3. A fowl passageway having a pivotally mounted bottom, spring means normally holding the bottom in a raised position, closures mounted adjacent the ends of the passageway, means connecting the closures and bottom for actuating them so that one fowl at a time may pass through the passageway, a pair of vertically hinged doors

disposed at the entrance end of said passageway, spring means normally retaining said doors in a closed position, and latch means for holding the doors in a partially open inwardly converging position whereby the doors will yield to permit 5 fowls to enter the passageway therethrough but will prevent fowls from passing outwardly therethrough.

4. A device of the class described comprising a casing having open ends forming an entrance 10 and an exit, a depressible platform hingedly mounted in the casing adjacent the entrance end and extending to adjacent the exit end of said casing, means for normally holding said platform in a raised position, closures hinged to said casing adjacent the ends of said platform, levers pivotally connected to said casing, links connecting said closures and platform to said levers whereby said closures will be alternately opened and closed by the movement of the platform, 20 flanges rising from the sides of said platform for slidably engaging the sides of said casing, a pair of hinged doors mounted at the entrance end of said casing, spring means normally holding said doors in a closed position, and latch means for 25 retaining said doors in a partially open inwardly converging position.

5. A device of the class described comprising a casing having open ends forming an entrance and an exit, a depressible platform hingedly 30 mounted in the casing adjacent the entrance end and extending to adjacent the exit end of said casing, means for normally holding said platform in a raised position, closures hinged to said casing adjacent the ends of said platform, link and lever 35 means connecting the said closures and platform whereby said closures will be alternately opened and closed by the movement of the platform, flanges rising from the sides of said platform for slidably engaging the sides of said casing, said 40 link and lever means comprising a T-shaped lever pivotally connected at the junction of its arms to each of the sides of said casing, links connecting the corresponding ends of each of said levers to one of said closures, a link connecting the other arm of each of said levers to said platform, and a link connected to one of said last mentioned arms and adapted to be connected to a counting mechanism whereby said mechanism will be actuated 45 in response to the movement of said platform.

6. A fowl passage comprising a casing having inlet and outlet ends, a platform pivotally mounted in the casing adjacent the inlet end and extending toward its outlet end, closure means hingedly connected to the casing adjacent the 55 ends of the platform, T-shaped lever means mounted in the casing, links connecting said closure means and platform to said lever means whereby one of said closure means will be closed and the other opened when the platform is depressed, and spring means normally holding the 60 platform in a raised position and normally holding one of the closure means in an open position and the other in a closed position.

7. A device as in claim 6, comprising a pair of 65 hinged inwardly opening doors at the entrance end of the casing, springs normally holding the doors in a closed position, and latch means for retaining the doors in a partly opened position whereby said doors will yield inwardly to permit 70 a fowl to enter the casing, but will prevent the fowl from passing outwardly therethrough.

HARVEY B. HARNAR.
